UNITED STATES PATENT OFFICE.

CHARLES SCHMIDT, OF CLEVELAND, OHIO, ASSIGNOR TO THE PEERLESS MOTOR CAR COMPANY, OF CLEVELAND, OHIO, A CORPORATION OF WEST VIRGINIA.

CARBURETER.

No. 882,170.

Specification of Letters Patent. Patented March 17, 1908.

Application filed February 15, 1906. Serial No. 301,169.

To all whom it may concern:

Be it known that I, CHARLES SCHMIDT, a citizen of the Republic of France, residing at Cleveland, in the county of Cuyahoga and State of Ohio, have invented a certain new and useful Improvement in Carbureters, of which the following is a full, clear, and exact description, reference being had to the accompanying drawings.

10 This invention relates to a carbureter for an explosive engine, especially adapted for use on automobiles where it is required that the engine shall be run at variable speed.

The primary object of the improvement is 15 to adapt a carbureter to automatically supply at any time the required volume of a suitable explosive mixture to permit the engine to be driven at any required speed.

The invention resides particularly in the 20 throttle valve and its associated mechanism; but it includes additionally certain novel means for increasing and regulating the supply of air as required for making an increased quantity of the explosive mixture.

25 The invention may be summarized as the construction and combinations of parts shown in the drawing and hereinafter described and claimed.

In the drawing, Figure 1 represents the 30 improved carbureter and some associated parts,—the throttle valve chamber, the mixing tube and a part of the float valve chamber being shown in central section.

Referring to the parts by letters, A represents the supply tank, and B a float-valve chamber both of ordinary construction.

C represents the spray plug through which the hydro-carbon in said float-valve chamber is delivered as a spray into the vertical 40 mixing tube D. The lower end of this tube is open, but of contracted area for the admission of air which assists in volatilization of the hydro-carbon spray and mixes with the vapor so formed to form the explosive 45 mixture. There are holes d in the side of the mixing tube near its lower end. A valve sleeve F embraces said lower end and has holes f in it. By turning said sleeve, the holes d may be entirely covered or opened 50 more or less to admit a greater or less quantity of air to the mixing tube. On the sleeve F is an arm f' to which may be attached an operating rod I. This rod is to be extended to any convenient point for its 55 operation.

The mixing tube is attached at its upper end to the throttle valve casing E which has an outlet e². Over this outlet is connected the branched pipe K which leads to the explosion chambers of the engine cylinders. 60 In this valve casing, between the point where the explosive mixture enters from the mixing tube, and the discharge outlet e², is an approximately balanced throttle valve G, having two tapered surfaces g and g' 65 which are opposed to the two tapered valve seats e and e', located on opposite sides of the outlet e². This valve is connected with two stems H, H' which pass respectively through holes in opposite ends of the valve 70 casing, one stem H being for connection with the manually operated throttle controlling mechanism, the other H' for connection with an automatic governor. Preferably a coiled spring H' embraces the stem 75 H' and thrusts against the valve casing and an adjustable nut h upon said stem, whereby this spring acts to move the throttle valve in the closing direction.

The throttle valve is tubular with openings 80 at both ends thereof so as to furnish free communication between the two parts of the valve casing at opposite ends of the valve. Preferably the end of the valve adjacent to the mixing tube is approximately conical and 85 provided with a plurality of slots g² through which the gas may flow into the valve and thence into that part of the valve casing at the opposite end of the valve.

In carbureters of the general type shown, 90 it is the suction of the pistons which draws the gasolene through the spray plug and which draws air into the mixing tube and which draws the mixture produced into the explosion chambers. In such carbureters, 95 as have been heretofore constructed, the flow of the gas mixture toward the explosion chambers tends either to open or close the throttle valve according as it is arranged. To counteract this tendency, springs have 100 been employed, but they have not proved entirely satisfactory in practice for the reason that as the speed of the engines increase the suction increases. If said springs are set to counteract the force of the flowing gas, 105 tending to open or close the throttle under certain conditions, the said spring will be too powerful or too weak to produce the desired result under other conditions—that is to say, when the engine is running either faster or 110

slower. With the construction herein shown, however, the valve is substantially balanced, and the flowing gas has substantially no influence upon it tending either to open or close it whatever may be the speed of the engine. The spring H^2 , therefore, when properly set, has precisely the same influence upon the throttle valve under one condition as under another. When the valve has been opened, the gas flows past the valve seat e to the outlet e^2 and it also flows through the valve G past the seat e' to the same outlet. A given movement of the valve, therefore, permits the flow of substantially double the quantity of the mixture which the same movement would permit if there were but one valve seat and, therefore, only one path through which said gas might travel. The variations in the speed of the engine may, therefore, be effected by the smaller movement of said valve. Another advantage of the described construction is that the mixture passing through the slots g^2 and thence through the valve and past valve seats e' becomes more thoroughly mixed—that is to say, the hydro-carbon vapor and air become more thoroughly mixed together than they would be except for this construction.

Most users of automobiles wish to have the engines continue to run when the vehicle is temporarily standing still. Ordinarily this result is produced by the failure of the operator to complete the closing of the throttle valve. In ordinary constructions it is necessary for him to determine the position in which he shall leave his throttle controlling mechanism to bring about the desired result. With the construction shown, however, the valve seats e , e' and the corresponding parts g , g' of the valve may be so formed that when the part g' of the valve is closed against the seat e' , there will still be a sufficient opening past the valve seat e to furnish just the necessary amount of mixture to the engines to keep them going under the described conditions. Of course, when such is the construction the way to stop the engines will be to turn off the spark. This result may be secured in a practical way by means of an adjustable sleeve e^3 which screws into the valve casing and carries the valve seat e' . The construction of automobiles is still in a more or less experimental condition, and it is not pretended that by practical use it has been determined beyond a doubt that the best construction is that in which one cannot entirely close the throttle. The construction shown in the drawing, however, with the adjustable sleeve e^3 is one which is adapted, as above stated, to be so adjusted that the throttle can be completely closed, or that it may be left open to any extent which experience shall show to be desirable.

The rapid volatilization of the hydro-carbon or other fuel used rapidly absorbs heat,

and thereby greatly diminishes the temperature of the gas and of the parts of the mechanism through which it flows. The freezing of the throttle valve to the valve seat is not an uncommon occurrence as the result of the action referred to. To counteract this tendency the valve casing E is provided with a water jacket J , which is connected by means of pipes j and j' in the water circulating system.

When the engines are running very fast the suction may be so great that the amount of air which may be supplied through the mixing tube is inadequate for the fuel which is drawn through the spray plug. To meet this emergency means are provided for admitting air to the mixing tube at a point above that at which the hydro-carbon spray enters said tube; and the opening through which air is admitted is controlled by an automatic valve. In the construction shown, there is a lateral branch D' of the mixing tube connected to it near its upper end, which branch serves as a valve casing. In the bottom of this casing is an opening d^3 through which air may be admitted; and this opening is normally closed by a valve M which is pressed against its seat by a spring m . This valve is secured to a stem which passes both up and down through adjustable plugs d^4 , d^5 in the valve casing. The spring m is compressed between the inner end of the upper plug and the top of the valve. By screwing this plug in or out the tension of the spring may be regulated. On the projecting lower end of the stem a collar m^2 is fixed; and above this collar, around the stem, is a small coiled buffer spring. When the valve opens, its opening movement is gradually checked, and ultimately stopped by said spring, which is compressed between the plug and collar. By screwing this lower plug in or out the extent of movement of valve M is controlled. The adjustment of plug d^4 determines the degree of rarefaction in the said valve casing required to cause the valve to open; and the adjustment of the plug d^5 determines how far said valve may open.

Having described my invention, I claim:

1. In a carbureter, the combination of a valve casing having an outlet, two valve seats which are located within the casing and on opposite sides respectively of said outlet, a sleeve which is adjustably secured within the casing and upon which one of said valve seats is formed, a valve provided with two faces which are respectively adapted for co-operation with the two valve seats within the casing, and means for operating said valve, there being fuel passages for the admission of the gas into the casing at both ends of said valve.

2. In a carbureter, the combination of a valve casing having an inlet and an outlet

and two valve seats on opposite sides of said outlet,—one of them being between said inlet and outlet, with a valve having surfaces opposing said valve seats, and having a fuel passage through it from one end to the other.

3. In a carbureter, the combination of a valve casing containing two valve seats, and having an outlet located between said valve seats, and an inlet at a point which is not between said valve seats, a longitudinally movable valve in said casing having two faces which are opposed to the said seats upon the casing, and having a longitudinal hole through it from end to end through which

15 gas may pass freely from the inlet end of the casing to the opposite end thereof, and means for moving said valve.

4. In a carbureter, the combination of a valve casing having an inlet at one end and 20 an outlet near the middle, and two valve seats located on opposite sides of the outlet opening, one of them being between the outlet and inlet, a sleeve adjustably secured within the casing upon which one of said 25 valve seats is formed, a valve having two valve faces adapted to respectively coöperate with the said valve seats on the casing, said valve having a longitudinal hole extending through it from end to end through which

30 gas may freely flow from the inlet end of the

casing to the other end thereof, and means for operating said valve.

5. In a carbureter, the combination of a valve casing having an inlet and an outlet and two valve seats on opposite sides of said outlet,—one of them being between said inlet and outlet, with a valve having surfaces opposing said valve seats,—said valve being tubular and having through one end a plurality of slots which communicate with the 35 interior of said valve.

6. In a carbureter, the combination of a valve casing having an inlet and an outlet and two valve seats on opposite sides of said outlet,—one of them being between said inlet and outlet, with a valve having surfaces opposing said valve seats, and having a hole through it from one end to the other, two stems secured to opposite ends of said valve and extending out through opposite ends of 45 said casing, and a spring engaging with one of said stems and acting thereon to move the valve.

In testimony whereof, I hereunto affix my signature in the presence of two witnesses.

CHARLES SCHMIDT.
